(57) **CLAIM**

The ornamental design of a light head, as shown and described.

DESCRIPTION

FIG. 1 is a perspective view of a light head;
FIG. 2 is a top view of the light head;
FIG. 3 is a front view of the light head, the opposite rear view
being identical;
FIG. 4 is a side view of the light head, the opposite side view
being identical; and,
FIG. 5 is the bottom view of the light head.
The broken line showing of the mounting bracket and the
screws is for the purpose of illustrating environmental struc-
ture for the light head and forms no part of the claimed design.
